CLAIM

The ornamental design for a solar wire light, as shown and described.

DESCRIPTION

FIG. 1 is a first perspective view of a solar wire light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion in FIG. 1. The broken lines shown in the drawings depict portions of the solar wire light in which the design is embodied that form no part of the claimed design. The broken lines of alternating length are for the purpose of illustrating the boundaries of the enlarged fragments shown in FIG. 9 and form no part of the claimed design. Symbolic breaks are shown at each end of the solar wire light and the appearance of any portion of the string light beyond the symbolic break lines forms no part of the claimed design.
